CIGARETTE PACKAGE

John H. MacMillan, Jr., Minneapolis, Minn.

Application March 5, 1936, Serial No. 67,314

1 Claim. (Cl. 229—16)

This invention relates to new and useful improvements in cigarette packages of the type comprising a flap whereby it may readily be opened and closed each time a cigarette is removed therefrom.

An object of the present invention is to provide an improved cigarette package, preferably constructed of a suitable paper, and the walls of which are so arranged and folded that when the package is closed, it is so strengthened and reinforced that the package may readily be carried in a pocket without danger of becoming distorted or collapsing, even though subjected to considerable pressure.

15 A further object of the invention is to provide a cigarette package constructed of flexible material and having a flap for closing the open end thereof, which flap is provided with inwardly folded edges which, when the flap is in closed position, strengthens the flap and also the upper end of the package.

20 A further object is to provide a cigarette package comprising a body portion composed of front, back, and side walls, and the back and side walls 25 of the body extending beyond the top of the body, and the extended side wall portions being adapted to fold over the extended back wall portion and cooperating therewith to provide a flap which may be folded over the mouth of the body and suitably secured to the front wall of the package to thereby close the package.

25 A further object is to provide an improved cigarette package provided with a flap for closing the open end or mouth thereof, and which flap is so constructed that when the package is closed, the body of the package is greatly strengthened, whereby it will withstand considerable pressure without danger of collapsing or becoming distorted, and whereby the cigarettes contained 30 therein are not readily bruised or otherwise damaged, while carried in said package.

35 Other objects of the invention reside in constructing a package or container from a single blank of material so scored and shaped that its 40 various sections may readily be folded to provide a package having an open end, and a closure for closing said open end; in the construction of the walls of the package which constitute the flap, whereby bellows-like folds are provided at 45 the juncture between the body and the flap, when the latter is folded over the top of the body and against the front wall thereof, thereby to strengthen and stiffen the upper end of the package so that when closed, it is not likely to be 50 come distorted when carried in a pocket; in the

means provided in the front wall of the package for exerting a slight pressure upon the contents or cigarettes in the package, thereby to retain them in position therein, when the package has been partially emptied; in the simple means 5 provided for retaining the flap in closed position; and in the simple and inexpensive construction of the package, as a whole, whereby it may be manufactured at small cost.

Other objects of the invention will appear from 10 the following description and accompanying drawings and will be pointed out in the annexed claim.

In the accompanying drawings, there has been disclosed a structure designed to carry out the 15 various objects of the invention, but it is to be understood that the invention is not confined to the exact features shown as various changes may be made within the scope of the claim which follows.

20 In the drawings:

Figure 1 is a plan view of the blank from which the package or container is made;

Figure 2 is a perspective view showing the blank folded to provide the completed package, 25 the flap being shown in open position;

Figure 3 is a perspective view showing the flap partially folded into closing position;

Figure 4 is a view showing the package filled with cigarettes and a pack of matches secured to 30 the front wall of the package;

Figure 5 is a perspective view showing the package completely closed;

Figure 6 is a vertical sectional view through the package, showing the matches concealed between the front walls of the package and the flap, and also illustrating in dotted lines, the 35 means provided in the package for retaining the cigarettes in position therein;

Figure 7 is a sectional plan view on the line 40 7—7 of Figure 6, showing the package partially empty;

Figure 8 is a top view of the package;

Figure 9 is a detail sectional view on the line 45 9—9 of Figure 6, showing how the material is folded upon itself at the lower corners of the package, when the blank is folded to provide the completed package; and

Figure 10 is a perspective view showing a package provided with a snap button for securing the 50 flap in closed position.

The novel cigarette package herein disclosed, is shown formed from a single blank of material, preferably shaped as shown in Figure 1. This blank comprises three main sections 2, 3, and 4, 55

section 2 forming the front wall of the package, section 3 the back wall, and section 4 the flap for closing the mouth of the package. A section 5 is defined by transverse score lines 6-6, and 5 constitutes the bottom wall of the package, and a section 7, defined by transverse score lines 8-8, provides the top wall of the package, when the mouth thereof is closed.

The blank is also shown provided with longitudinally extending score lines 9-9, which extend from end to end of the blank and along which the blank is bent to provide the corners of the package. V-shaped notches 11 are preferably provided in the opposite edges of the blank 15 and have diagonal score lines 12 extending from the bottoms thereof to the points of intersection between the score lines 6 and 9. Diagonal score lines 13 are provided in the blank at the ends of the section 7, for purposes subsequently to be 20 described.

To construct the package, the section 2 of the blank is folded over the section 3, along the score lines 6-6, and the marginal sections 14 are then folded inwardly and suitably secured together by 25 gumming, to thereby form the side walls of the package, as will readily be understood by reference to Figure 2. The diagonal score lines 12, at the bottom of the notches 11, cause a portion of the material to be folded upon itself, as clearly 30 illustrated in Figure 9, so that when the marginal edge portions 14, which constitute the side walls of the package, are suitably secured together, the section 5 between the score lines 6-6 will constitute the bottom wall 15 of the package.

An important feature of the present invention resides in the novel construction of the means provided for closing the mouth of the package, and which also functions to reinforce and strengthen the package, when closed. This 40 closure means will hereinafter be referred to as the flap. The flap, generally indicated by the numeral 16, is composed of section 6 of the blank, and portions of the marginal edge portions 14, which represent the side wall portions 22 of the flap. 45 When the sections of the blank are folded into the positions shown in Figure 2, it will be noted that the flap 16, which, in this figure, is shown open, is aligned with the back wall 18 of the package (section 3 of the blank). The front wall 21 of the package is formed by section 2, and the bottom wall 15, by section 5. It will also be noted that the side wall portions 22 of the flap are, in reality, extensions of the side walls 23 of the package body, which latter side walls are also 55 composed of portions of the marginal edge portions 14 of the blank. When the flap is open, the side walls 22 and 23 of the flap and package body, respectively, are aligned, and the wall portions 22 may assume the positions shown in Figure 2. 60 If desired, the corners 28 of the side walls 22 may be folded into contact with the wall of the flap 16 and be secured thereto.

When the flap 16 is closed, its side walls 22 are folded inwardly against the flap, as shown in 65 Figure 3, whereby bellows-like folds 24 are provided between the side wall portions 22 and 23, caused by the diagonal score lines 12. These bellows-like folds cooperate with the inwardly 70 bent side wall portions 22 of the flap to strengthen the upper or top end of the package or container, when the flap is folded into closing relation, as shown in Figures 5 and 6, whereby the package 75 cannot readily be distorted or collapsed, when an abnormal pressure is applied thereto, which may

frequently happen when the package is carried in a pocket or purse.

To close the mouth of the package, the flap is folded over the open end or top of the package, into engagement with the front wall 21 thereof, as shown in Figures 5 and 6. A pack of matches 17, is preferably secured to the front wall 21 of the package, and is concealed by the flap 16, as best shown in Figure 6. One of the walls of the package as, for example, the bottom wall 15, is provided with a suitable match-scratching surface, indicated by the numeral 20.

Means is provided for securing the flap in closed position and preferably consists of a flexible element 26, shown having its terminals suitably secured to the ends of the flap, as best illustrated in Figure 2, whereby the element 26 may be stretched over the lower end of the package, when the flap is in closed position, as shown in Figures 5 and 6, thereby to retain the flap in such 20 position.

Another important feature of the invention resides in the means provided for retaining the cigarettes in upright position within the package or container, when the package has been partially 25 emptied. Such a means is shown in Figures 2, 6, and 7, and may consist of inwardly bending a portion 27 of the front wall 21 of the package. To thus inwardly bend the portion 27, the section 2 of the blank is slotted as shown at 28 in 30 Figure 1, whereby the portion 27 may readily be bent inwardly to the dotted line position, shown in Figure 7. When the package is filled, the inwardly bent portion 27 is folded flatly against the front wall 21 of the package, as clearly 35 illustrated in Figure 6.

Figure 10 illustrates a package of slightly modified construction, wherein a suitable snap button, generally indicated by the numerals 29 and 31, is provided for retaining the flap 32 in closed 40 position. The flap, shown in Figure 10, is substantially the same in construction as the one shown in the previous figures, with the exception that the marginal edge at the end thereof, is bent inwardly, as shown at 33, to strengthen the wall 45 so that the part 29 of the snap button may be suitably secured thereto.

The novel cigarette package herein disclosed, has been designed on an engineering basis, whereby the walls thereof provide the utmost in strength 50 and rigidity when the package is closed, and whereby it may be conveniently carried in the pocket without danger of becoming distorted or collapsing. Ordinary cigarette packages, when carried in the pocket, quickly become distorted 55 and press out of shape to the extent that the cigarettes therein often become mutilated which, obviously is undesirable.

In the unique carton herein disclosed, the portions of the blank which constitute the flap are 60 scored in such a manner that when the side wall portions 22 of the flap are folded inwardly, as shown in Figure 3, the portions thereof adjacent to the mouth of the package, will fold upon themselves to provide the bellows-like folds 24, which 65 folds, as hereinbefore stated, cooperate with the flap 16 to so strengthen and stiffen the upper end of the container that the package will withstand considerable pressure without danger of becoming distorted or collapsing, and whereby the cigarettes in the package will be protected against damage until all of the cigarettes of the package 70 have been removed therefrom.

The construction of the package presents the 75 utmost in simplicity, whereby it may be manu-

2,107,049

factured at very small cost, so that the package may be used in lieu of the usual form of package now commonly used, without materially increasing the selling cost of the cigarettes.

5 I claim as my invention:

A blank for use in forming a cigarette package comprising a substantially rectangular member of fibrous material, said blank having substantially straight side edges and end edges arranged at 10 right angles thereto, longitudinally disposed score lines arranged inwardly of and parallel to the

side edges of the blank to permit the marginal side edges to be folded to form side walls of the package, transverse score lines dividing the blank into a front wall portion, a bottom wall portion, a back wall portion, a top wall portion and a closure flap in the order named, and diagonal score lines on said marginal side edge portions to facilitate forming the bottom wall and top wall of the package.

JOHN H. MACMILLAN, JR. 10
